(57) CLAIM

The ornamental design for a tea infuser, as shown and described.

DESCRIPTION

FIG. 1 is a front, right, and top perspective view of a tea infuser, showing my design.

FIG. 2 is a rear, left, and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a partial enlarged view of an area labeled 9 in FIG. 1 comprising a connector and a hole; and,

FIG. 10 is a perspective view of the tea infuser in FIG. 1 wherein an upper part of the tea infuser is open.

The broken lines shown in the drawings are included for the purpose of illustrating portions of the tea infuser that form no part of the claimed design.
